US00D508018S

(12) **United States Design Patent** (10) Patent No.: **US D508,018 S**
(45) Date of Patent: ** *Aug. 2, 2005

(54) **BATTERY**

(75) Inventor: **Hiroaki Yokota**, Tokyo (JP)

(73) Assignee: **Sony Corporation**, Tokyo (JP)

(*) Notice: This patent is subject to a terminal disclaimer.

(**) Term: **14 Years**

(21) Appl. No.: **29/206,521**

(22) Filed: **Jun. 2, 2004**

(51) LOC (8) Cl. **13-02**

(52) U.S. Cl. **D13/103**

(58) Field of Search D13/103, 107,
D13/110, 119, 184; D14/188; 429/96-100,
163, 176

(57) **CLAIM**

The ornamental design for a battery, as shown.

DESCRIPTION

FIG. 1 is a perspective view of a first embodiment of a battery showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of a second embodiment of a battery showing my new design;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof;

FIG. 14 is a bottom plan view thereof;

FIG. 15 is a perspective view of a third embodiment of a battery showing my new design;

FIG. 16 is a front elevational view thereof;

FIG. 17 is a rear elevational view thereof;

FIG. 18 is a left side elevational view thereof;

FIG. 19 is a right side elevational view thereof;

FIG. 20 is a top plan view thereof;

FIG. 21 is a bottom plan view thereof;

FIG. 22 is a perspective view of a forth embodiment of a battery showing my new design;

FIG. 23 is a front elevational view thereof;

FIG. 24 is a rear elevational view thereof;

FIG. 25 is a left side elevational view thereof;

FIG. 26 is a right side elevational view thereof;

FIG. 27 is a top plan view thereof; and,

FIG. 28 is a bottom plan view thereof.
